CONTROL MECHANISM FOR GUN TRAINING
APPARATUS

Lambert S. Linderoth, Jr., Marblehead, Mass., assignor to United Shoe Machinery Corporation, Flemington, N. J., a corporation of New Jersey

Application January 14, 1943, Serial No. 472,387

8 Claims. (Cl. 89—41)

1

This invention relates to control mechanisms, and more particularly to mechanism for operating one or more control members, the movements of which effect the positioning of a movable device such as, for example, a gun, tool or like implement. The herein illustrated embodiments are shown as associated with the control members of a power-operated gun training apparatus of the type disclosed, and claimed, in a copending application for United States Letters Patent, Serial No. 442,688, filed on May 12, 1942 issued October 8, 1946 as Patent No. 2,409,041, jointly by the present applicant and Fred V. Hart, but it is to be understood that, in its broader aspects, the invention is not limited in its applicability to that particular apparatus.

In the apparatus disclosed in the aforementioned application, the mechanism for controlling the operation of the gun training motors includes two control members the movements of which effect a positioning of the guns in accordance with movements of a remotely located control handle, directly connected to said control members, so that the operator, by moving the control handle, is enabled to impose a space control on movements of the gun by the motors. This space control results from the action of follow-up mechanism associated with the movable control members and the motors, the arrangement being such that movements of these control members are exactly followed by the motors and, consequently, by the guns themselves which are driven thereby. A principal object of the present invention is to provide control mechanism for operating control members of this general type, i. e., members the movements of which effect a corresponding positioning of a device, so as to impose both a space and a rate control on the movements of a device. As used in this specification, and in the appended claims, the term "space control" means that movement of the controlling member a predetermined distance from neutral position results in a corresponding movement of the controlled member, i. e., the position in space of the controlled member is determined initially by the position of the controlling member. The term "rate control," on the other hand denotes a condition where a predetermined movement of the controlling member, from neutral position, effects a continuing movement of the controlled member at a rate determined by the displacement of the controlling member from its neutral position. These are the meanings of these terms as understood in the art to which this invention relates.

2

With this purpose in view, the control mechanism of this invention is provided with a control handle for operating control members to impose a space control on their movements, and hence upon the positioning movements of a device controlled thereby, in accordance with the movement of the control handle; together with additional means for so moving the control members as to impose a rate control on their movements, and likewise on the positioning movements of the device, in accordance with the movement of the control handle. More particularly, movements of the control handle are transmitted to the control members, each of which is associated with a follow-up mechanism for controlling a fluid-pressure operated gun training motor, through a differential means. Preferably, and as shown in the herein illustrative embodiments of the invention, each differential means comprises a floating lever connected at an intermediate point to a control member, at one of its ends to the control handle and at its other end to a rate motor having a controlling means operatively associated with the control handle. The arrangement is such that movement of the control handle first effects a corresponding initial displacement of one, or both, of the control members, thus imposing through the follow-up mechanism, or mechanisms, a space control on the positioning movement of the device by one, or both, of the gun training motors. This movement of the control handle operates the controlling means of one, or both, of the rate motors so that movement of the control member, or members, is thereafter continued at a speed dependent upon the extent of initial movement of the control handle and a rate control is thus imposed on the movements of the control member. Inasmuch as movements of the control members are followed exactly by the movements of the gun, movement of the control handle will, therefore, impose a corresponding rate control on the positioning movements of the gun.

Preferably, and as herein shown, the rate motors are fluid-pressure operated and each controlling means therefor comprises a valve having a valve member movable from a closed position to control the flow of pressure fluid to, and exhaust from, opposite sides of its associated motor. Means are also provided for rapidly reciprocating the movable valve member, equal distances in opposite directions from its closed position, so as to apply a series of balanced pressure impulses alternately to opposite sides of the motor, together with means for changing the posi-

tion of these reciprocations with respect to the closed position, by movement of the control handle, for the purpose of selectively unbalancing the pressure impulses on one side or the other of the motor and thereby controlling the direction and speed of operation of the motor. As a result static friction in the rate control valves, and also throughout the whole system, is eliminated and a very accurate and smooth controlling action is obtained.

The above, and other, objects and features of this invention will appear in the following detailed description of the illustrative embodiments thereof shown in the accompanying drawings, and will be pointed out in the claims.

In the drawings,

Fig. 18 is a schematic view of a modified control mechanism shown in Figs. 11—13, inclusive.

The herein illustrated embodiments of the invention are, as above indicated, disclosed as applied to power-operated apparatus for training two machine guns mounted in an airplane. The means for mounting the two guns for universal movement about two axes at right angles to each other, the power-operated apparatus for training the guns, by swinging them about these axes, the mounting of the associated sight, and the linkages for maintaining the optical axis of the sight parallel with the guns are essentially the same as those disclosed in the aforementioned copending application.

Referring to Figs. 1 and 2, the two guns G, G are mounted for universal movement inside of the fuselage F of an airplane so as to project through an opening O therein in the following manner. Extending upwardly from a plate 20, secured to a cross-member 21 of the fuselage structure, are two posts 22 on each of which there is rotatably mounted a sleeve 24. Pinned to the top of each sleeve is a block 26 which carries two side plates 28 joined at their upper ends by a second block 30. Each of the blocks 30 is rotatably mounted in a bearing 32 which is carried by a plate 33 secured to an upper cross-member 34. Clamped to the lower ends of the sleeves 24 are two arms 36 and 38 (Fig. 5) joined by a cross-link 40. The blocks 30 are likewise connected by a cross-link 41 (Fig. 2). The side plates are each provided with forwardly extending ears 42 and pivoted to each of these ears, on a pin 46, is one end of an arm 44. Each of the two guns is mounted on, and between, two of these arms by means of bolts 48 passing through the adapter bars 50 of each gun assembly, extended bearing portions 52 of the arms and clamping plates 54.

Secured to the opposite end of each arm 44 is a downwardly extending strap 56 and each pair of these straps is connected to a slide 58 mounted on the sleeve 24 and held against rotation with respect thereto by means of a key 60. These two slides are rotatably connected to the opposite ends of a yoke member 62, which is itself secured to a crosshead 64 slidably mounted on the exterior of a cylinder 66, by means of collars 61, positioned between thrust flanges 63, 65 on the slides, Figs. 1 and 2. As will be apparent, vertical movement of the crosshead will swing the two guns together about the horizontal axis provided by the pins 46 while movement of the arm 36 (Fig. 5) will swing the guns about the vertical axes provided by the posts 22 and bearings 32. During these training movements the two guns will be maintained in parallelism by means of the yoke 62 and crosslinks 40 and 41, as will be readily understood.

These training movements are effected by means of two fluid-pressure motors, the one for swinging the guns about their horizontal axes, hereinafter referred to as the elevation motor, comprising a piston 68, in cylinder 66, which is connected to the crosshead 64 by means of a piston rod 70 (Fig. 3). The motor for swinging the guns about their vertical axes, hereinafter called the azimuth motor, comprises a cylinder 72, pivoted to a bracket member 74 mounted on the plate 20, and a piston 76 which is connected to the arm 36 by means of a piston rod 78 (Fig. 5). Referring to Figs. 9 and 10, in which these motors and their controlling valves are shown schematically, cylinder 72 is connected to a reversing valve 80 by pipes 82, 84 while cylinder 66 is connected to a similar reversing valve 86 by pipes 88, 90, each of these valves being connected to a source of pressure fluid (not shown) and to exhaust by means of pipes 92, 94.

The valves 80 and 86 each have a movable valve member 96, provided with an operating rod 98, projecting from the valve housing as shown, Figs. 6, 9 and 10, and slidably mounted within a sleeve 100 held in the housing by means of threaded thimbles 102, 104. This sleeve is provided with spaced grooves 106, 108 and 110 (Fig. 6) connected to exhaust line 94, to pipes 82 and 84, and to pressure line 92, respectively, and the valve member has two enlarged portions 112 and 114

each just wide enough to cover a groove 108. Accordingly, and as will be readily understood by persons skilled in the art, movement of the reversing valve member to the right or left of the neutral position in which it is shown will result in admission of pressure fluid to one or the other end of the associated motor and exhaust the other end, exhaust grooves 106 being connected by a duct 116 in the housing, as shown.

Pivoted to the rod 98, of the valve 80, is a floating lever 120, and a similar floating lever 122 is likewise pivoted on the rod 98 of valve 90. At one end, the lever 120 is connected to a valve operating lever 124 by a link 126 and, at its opposite end, this lever is connected, by a link 129, to the arm 36 (see Figs. 2, 4 and 10). Likewise, one end of lever 122 is connected to another valve operating lever 128, by means of links 130, 132 and bell crank 134, while its opposite end is connected to the crosshead 64 by a link 136 (see Figs. 3, 4 and 9). Referring to Figs. 1 and 4, the valve operating levers 124 and 128 are fulcrumed in bearings on a plate 138 which is secured to a cross-member 140 of the airplane. This plate is of considerable width so that these arms are located on the opposite sides, and extend rearwardly, of an armored wall 142 which separates the gunner's compartment from the space occupied by the guns.

By connecting the valve operating levers to their associated valve operating rods by means of floating or "differential" levers, as above described, a follow-up or "servo" action is obtained. That is, movement of either of the valve operating levers, as for example, the lever 124, will swing the lever 120 about its point of attachment to the link 129 and, through rod 98, will shift the valve member 96, thus causing the piston 76 to swing the arms 36 and 38 in one direction or the other. This movement of the arm 36, however, will immediately swing the lever 120 in the opposite direction and return the valve member to closed position. The operation of valve operating lever 128 to control piston 68 is the same and thus the direction and extent of each motor is determined by the direction and extent of movement of its associated valve operating lever. The arrangement is such that movement of the lower ends of levers 124 and 128, as viewed in Figs. 9 and 10, to the right or left and up or down, respectively, as indicated by legends thereon, will cause the pistons 68 and 76 to impart corresponding training movements to the guns in azimuth and elevation. The speed of movement of each motor is likewise determined by the speed of movement of its associated valve operating lever since, as will be apparent, the displacement of the valve operating rod, at any instant, and hence the valve opening, will depend upon the amount that movement of the operating lever is kept ahead of the movement of the motor piston. The levers 124 and 128 thus function as control members, the movements of which effect the positioning of the guns, in the same manner as the two bell-crank levers 136 and 149 provided in the apparatus disclosed in the above mentioned application. Adjustable stops 144 (Fig. 4) are provided for each rod 98 for limiting the maximum speed of training movement as desired.

A sighting device S (Fig. 1), is pivotally mounted adjacent to a window W, and above the gun, on a yoke 146 arranged for turning movement relative to a fixed part 148 of the plane. The optical axis of the sighting device is maintained parallel to the axes of the guns by means of the

following connections. Link 150 connects one end of a lever 152 to a rod 154 secured to the crosshead 64 and guided in a bearing bracket 156. The other end of this lever is connected to a rod 158, the vertical displacement of which, through bell crank 160, link 162 and arm 164, swings the sight about its horizontal axis. The yoke 146, and with it the sight, is swung about a vertical axis, by means of a link 166 extending between an arm 168 on the yoke and an arm 170 carried by a shaft 172 secured to one of the blocks 30.

The apparatus so far described is substantially the same as that disclosed in the above-mentioned application, to which reference may be made for a more detailed description of certain of the parts and a fuller explanation of the mode of operation, and provides mechanism for obtaining a space control of the operation of a plurality of power-operated means for training a gun. In the apparatus disclosed in said prior application, direct mechanical connections from a single control handle to the two bell-crank levers, which, as noted above, correspond in function to the levers 124 and 128, are provided and space control of the training movements of the guns about two axes at right angles to each other is thus obtained.

For moving the two valve operating levers 124 and 128 by means of a single control member, and in such a manner as also to obtain a rate control of the gun training movements, the following mechanism is provided. The single control member comprises hand grips 180 joined by a crossbar 182 and mounted for pivotal movement on a shaft 184 carried by upstanding portions 186 of a cylindrical member 188 (see Figs. 1, 4, 7, 9 and 10). The member 188 is rotatably mounted in a bearing portion 190 of a supporting frame 192 and has a downwardly and forwardly extending arm 194 and a laterally projecting arm 196. Extending laterally, from opposite sides of the frame, are two rods 198, 200, on which are mounted sliding blocks 202, 204 (Figs. 4, 9 and 10). The arms 186 are offset from the vertical axis of member 188 and secured to the shaft 184 is an arm 206. Also mounted on the frame are two fluid pressure motors 208, 210 comprising cylinders 212, 214, pistons 216, 218 and piston rods 220, 222, respectively (Figs. 9 and 10).

Pivoted at one end to the block 202 is a floating or "differential" lever 224, the opposite end of which is forked to embrace a pin 226 carried by the piston rod 222 of motor 210, and, at about its mid point this lever is connected to the valve operating lever 128 by means of an adjustable link 228. As has previously been explained, movement of the lever 128 controls the operation of the gun elevating motor, comprising piston 68 and cylinder 66, with a follow-up or servo action, and this lever will hence be referred to as the elevating servo lever to distinguish it from the other valve operating lever 124 which will be called the azimuth servo lever, since it controls the operation of the azimuth motor, comprising piston 76 and cylinder 72.

The arm 206 is connected to the block 202, by means of links 230, 232 and a bell crank 234, mounted on frame 192, so that rocking movement of the shaft 184, by handle 180, will shift this block along the rod 198, and, through lever 224 and link 228, will move the elevating servo lever 128, thus effecting an initial displacement of the gun by the elevating motor. This initial displacement of the block 202 and lever 128 will corre-

spond in speed, direction and extent to the speed, direction and extent of rocking movement of the handles 180, as will be apparent from the legends on Fig. 9, and, from the above explanation of the control function of the lever 128, valve 90, differential lever 122 and piston 68 of the elevating motor, will produce a corresponding movement of the guns about their horizontal axes. Thus, movement of the handles 180, in the first instance, effects a corresponding displacement of the lever 128 which imposes a space control on the movements of the gun by the elevating motor.

Rate control of the displacement of the lever 128, and on the operation of its associated elevating motor, is obtained in the following manner by the motor 210, which will be referred to herein-after as the elevation rate motor. Also mounted on the frame 192 is a reversing rate valve 236 which is connected to the source of pressure fluid (not shown) by a pipe 238 and to exhaust by a pipe 240. The valve has two outlets 242, 244 which are connected to opposite ends of the cylinder 214, by pipes 243, 245, and a movable valve member 246 for controlling the direction and rate of the flow of pressure fluid to and exhaust from the motor 210. Movement of the handles 180 is transmitted to the movable valve member by means of an arm 248 and a link 250, connecting the arm to the bell crank 234, and the arrangement is such that, when the handles are moved, in either direction, the valve member 246 is shifted from the neutral position, in which it is shown in Fig. 9, to start the rate motor 210 in operation. For example, if the handles are rocked a predetermined amount in a clockwise direction (Fig. 9), valve member 246 will be shifted to the right and pressure fluid will be admitted to the right-hand end of cylinder 214 and exhausted from the left-hand end. This will cause piston 218 to move to the left, carrying with it piston rod 222 and the lower end of the differential lever 224, at a rate dependent upon the amount of displacement of the valve member which, in turn, is determined by the amount of angular movement which was imparted to the handles initially. The block 202 being held fixed, by the connections back to the handle when movement of the handles is stopped, this movement of the lower end, as viewed in Fig. 9, of the differential lever will continue the movement of the elevating servo lever 128 in the same direction in which it was initially displaced by the lateral shifting of the block 202 to the left that, in the first instance, was effected by the angular displacement of the handles. Also, the stopping of movement of the handles will hold the rate valve open so that the rate of movement of the lower end of the differential lever and of the servo lever 128 will be determined by the amount of handle displacement.

If the handles are moved counterclockwise the same results will be obtained with the directions of movement of the parts reversed. The range of movement of lever 128 is limited by stops 252, 254, formed on a block 256 fixed to the rod 198, and, when the lever engages either of these stops, the continued operation of the rate motor will bring the handles back to their original position and, at the same time, return the valve member 246 to neutral position, thus stopping the rate motor. These stops, as well as similar stops 253, 255, on a block 257, associated with the traversing servo lever 124, are so arranged that movements of the gun in both elevation and azimuth are kept with-

in desired limits. Auxiliary safety stops 251 and 259 (Figs. 4, 7 and 9) are also provided for limiting the movements of the handles 180. From the foregoing it will be seen that by swinging the handles 180, in a vertical plane about the axes provided by shaft 184, the operator is able to impose both a space and a rate control on the operation of the elevating motor and, as a consequence of this, on the elevating movements of the guns about the axes of pins 46.

Similar mechanism is also provided for controlling movements of the gun in azimuth. The arm 194 is connected, through a link 260, to the block 204 (Figs. 7, 4 and 10), and movements of this block by the handles are transmitted to the servo lever 124 by a differential lever 262, pivoted at one end to the block and having its opposite end forked to embrace a pin 264 in the piston rod 220 of the azimuth rate motor 208, and a link 266. The operation of this motor is controlled by a rate valve 268 which is exactly like rate valve 236, having outlet ports 242, 244, connected to the opposite ends of cylinder 212 of azimuth rate motor 208, by pipes 243, 245, and to the source of pressure fluid (not shown) and to exhaust, by pipes 238 and 240, respectively. This valve also has a shiftable valve member 246 which is operated by an arm 274, in a manner which will be described below. This arm is connected to the arm 196 by a link 276. Accordingly, when the handles 180 are swung either to the right or to the left the lever 124 is initially displaced a corresponding amount and, at the same time, the rate motor is started to continue movement of the lever at a rate determined by the initial movement of the handles.

The two rate valves are exactly alike and similar reference characters have been applied to the like parts of each valve. Referring to Fig. 8, in which one of these valves is shown in section, the casing is provided with a longitudinal bore 280 in which an inner sleeve 282 and an outer sleeve 284 are positioned by means of threaded thimbles 286, 288. The movable valve member 246 is slidable axially in the inner sleeve, on piston portions 290, 292, 294, 296, by means of a nut 298, to which either the operating arm 248 or 274 is clamped. This nut is rotatably mounted on an extension 301 on one end of the member 246, between flange 303 and a nut 300, and has threads 302 engaging a threaded portion 304 on the thimble 286. Rotation of the nut 298 will translate the valve member axially in the sleeve 282. In Figs. 9 and 10 this action is schematically illustrated as a direct reciprocation by the arms 248 and 274 which are there shown as pivoted to the frame 142. Seals 306 surround the extension 301 and a similar extension 303 on the opposite end of the member 246. The inner sleeve is formed in three sections which, when assembled in the housing, provide five axially spaced external grooves 310, 312, 314, 316, 318 that communicate directly with five similar external grooves 320, 322, 324, 326, 328, formed on the exterior of the outer sleeve 284. The inner sleeve also has two internal grooves 330, 332 and between each of these grooves and its associated external groove 312 or 316 there is a slot 334, cut before the three sections were assembled. The other external grooves 310, 314 and 318 communicate directly with the interior of the sleeve and the spaces between the piston portions 290, 292, 294 and 296. The piston portions 292 and 294 are so spaced that their facing edges just cover the internal grooves 330, 332, when the

valve member is in the neutral position shown, and are traversed by narrow, gradually shallowing, kerfs 336 which emerge back of the facing edges of the piston portions at distances just equal to the width of the grooves 330, 332. Grooves 322, 326 are connected to the pipes 243 and 245, leading to the rate motor to be controlled by the valve through the openings 242 and 244, respectively, groove 324 is connected to the pressure line 238 and grooves 320, 328 to the exhaust line 240. In the illustrated construction, the connection of groove 320 to exhaust is by way of an axial and two radial ducts 340, 342, 344 in the valve member 246, this construction being such that a separate exhaust connection, communicating with groove 320, could be provided on the housing, if desired.

When either of the valve members 246 is displaced from the neutral position shown (Fig. 8), say upwardly, for example, the piston portion 292 will uncover the groove 330 and slot 334, associated with the groove 312, and pressure fluid will flow, through this slot, groove 312 and groove 322, pipe 243, to one end of the motor cylinder. At the same time, kerf 336 on piston 294 will overlap groove 322 so that pressure fluid, from the opposite end of the motor cylinder, can flow from pipe 245 through groove 326, groove 316, slot 334, groove 332, kerf 336, and grooves 318 and 328, to exhaust pipe 240. The effective area of the opening provided by the kerf 334 from groove 332 varies directly with the amount of displacement of the valve member and thus meters the flow of pressure fluid to exhaust, this metering effect continuing, as the displacement of the valve member increases. There being a closed circuit between the opposite ends of the motor and the valve it will be obvious that the speed of operation of the motor piston will be determined by the rate of flow of pressure fluid from the motor to exhaust. The area of each slot 334 is greater than the maximum effective area of its associated kerf 336 so that the latter always determines the speed of operation of the motor. Since the effective area of the kerfs 336 depends upon the amount of displacement of the valve member from neutral position it follows that the speed of operation of the rate motor is proportional to the amount of movement of the control handles.

In operating the apparatus to aim the guns at a moving target, the gunner grasps the handles 180 and observes the target through window W. Assuming, for example, that the guns are in the position shown in Fig. 1 and that a target is observed above and to the left of the direction in which the guns, and also sight S, are pointing, to bring the guns quickly to a position in which they will point toward the target, the gunner swings the handles down and to the right. This causes the gun training motors to move the guns so that their back ends, which are nearest the gunner (Fig. 1), are likewise moved down and to the right, by the space control that is thus imposed on the motors by this initial movement of the handles, and the guns pointed generally toward the target. It will be noted that this movement of the handles corresponds in direction to that which the gunner would impose on the guns themselves if he were moving them directly by their hand grips H.

If this initial movement of the handles has been properly gaged, the target will be within the field of view of the sighting device, which, of course, has followed the movement of the

guns, but to one side or the other, and above or below, the crosshairs or reticle of the sight. The target will also appear to be moving across the field of view of the sight in a direction and at a speed which will depend on the relative speeds of the target and the gunner's airplane, the angle between their lines of flight, and also the angular rate of movement of the guns under the rate control which is now being imposed on the gun training motors by the rate motors. As a result, the target will seem to be either coming into closer alignment with the optical axis of the sight or departing from such alignment. In the former case, the gunner will gradually decrease the rate of movement of the gun by moving the handles back toward their original position an amount sufficient to match their rate with the target rate at the instant the line of sight of the sight, and also the line of fire of the guns, intersect the line of movement of the target. If this is done the guns will keep on and thus "track" the target so long as its speed or course, or the speed or course of the gunner's plane, do not change. In making this adjustment of the rate control the gunner may slow the gun movement down to a point where the target will appear to cross the line of sight and start to move away on the opposite side. This will be immediately corrected by a return movement of the handles, in the original direction, which not only speeds the guns up, by the change in the speed of operation of the rate motors and the resulting rate control function, but also bodily shifts them back toward the target by the space control function.

On the other hand, the target, when it is first picked up in the sight, may appear to be moving away from a position of alignment with the optical axis of the sight. In this case the handles are given a further displacement, in the original direction, which bodily moves the guns, space control, toward the target, and, at the same time, increases the speed of movement of the guns, rate control, eventually bringing the line of sight, and line of fire, on the line of movement of the target, with the guns moving at a rate to track and keep on the target.

These movements of the handles first to bring the guns approximately on the target and then to adjust the rate of movement of the guns so as to track the target are made automatically by the gunner as he observes the target through the sighting device, the combination of space and rate control affording an "aided" tracking function making it possible for the gunner quickly to get on the target, closely to track the target, and also easily to follow changes in the speed and/or direction of movement of the target by slight movements of the control handle.

In Figs 11 to 18 a modified form of control mechanism for operating the servo levers 124, 128 is shown. This mechanism is contained within a compact housing 400 which is adapted to be mounted in the gunner's compartment C just in back of the armored wall 142 and between the rearward portions of the two servo levers. The housing has top and bottom walls 402, 404, connected by vertically extending post members 406, 408, 410, and 412, the openings between these post members being closed by removable cover plates 414 (Figs. 11 and 13), and cross members 416, 418 extending between the post members 406, 410 and 408, 412, respectively.

The control handles 420 are pivotally mounted on the outside of two rearwardly and upwardly

636 which is connected to one end of a differential lever 638. The opposite end of this differential lever is connected to an arm 639 extending downwardly from a hub 640 which is also journaled on the shaft 628. This hub has a second arm 642 in which a pin 644 is mounted and, adjacent thereto on the shaft, there is secured a collar 646 having a flange 648 provided with an ear 650. Wrapped around the shaft and having one end anchored thereto is a torsion spring 652 the opposite end of which is secured to a pin 654 in a disk 656 which is rotatably mounted on the shaft. This disk has an ear 658 and is positioned adjacent to the hub portion 660 of an arm 662 on which there is mounted a pin 664. The pins 644 and 664 engage the ears 650 and 658 in the same manner as pins 576 and 578 engage ears 566, 574 in the yieldable coupling shown in Fig. 14, and so that angular movement of the arm 662 will be transmitted to the arm 642, and thence to arm 639, through spring 652. In Fig. 18 these yieldable couplings have been omitted and the arms 552, 590 and 639 and 662 represented as being formed integrally as bell-crank levers and in fact these parts could be so constructed, if desired. However, by providing these yieldable couplings, the danger of damaging the parts should the servo levers 124 or 128 become jammed is avoided. The arm 662 is connected to the piston rod 452 of the azimuth rate motor by means of a sliding block 666 and pin 668 and a link 670 extends between the midportion of the differential lever 638 and servo lever 124. The upstanding lever 624 is also connected, by link 672, to one arm of a valve operating bell crank 674 the other arm of which is connected, by a link 676, to a second vibrating or "dithering" lever 678. This mechanism operates to impose space and rate control on the movements of the servo lever 124, which correspond in speed, direction and extent to movements of the control handles, and hence upon the operation of the azimuth motor in the same manner as such control is imposed on the elevating motor by the mechanism just described above.

Returning now to the manner in which the rate control valves operate and referring to Figs. 12, 13 and 18, the two bell cranks 604 and 674, by means of which movements of the control handles are imparted to the valves, are each pivoted on a post 680 having a base 682 that is clamped to the upper ends of the two valve sleeves 460. The vibrating or "dithering" levers 610 and 678 are pivotally connected to the stems 528, 530 of the two valve members 522 and also to a crosshead 684 (Fig. 13). This crosshead is connected to an eccentric 686 by means of a connecting rod 688 and slide 690. The eccentric is rotated at a high rate of speed by a motor 692 so that the right-hand ends of the levers 610 and 678 are vibrated at a very rapid rate.

When the control handles are in neutral position, as shown in Figs. 11 and 18, the bell crank levers 604 and 674 will occupy the positions in which they appear in Figs. 12 and 18 and, as a result of the above vibrating movements which are imparted to one end of these levers, the other end being held fixed, the valve member operating rods will be reciprocated back and forth from mid-position. In Fig. 16 the valve member 522 is shown at one extremity of its reciprocation in which position the slit 518 is uncovered a small amount on the exhaust side of the piston portion 524 while slit 520 is uncovered an equal amount on the pressure side of piston portion

526. Fig. 18 shows both valve members 522 in this position. As the eccentric 686 rotates a half turn, the valve members will be displaced equal distances on the opposite sides of their mid-positions so that ports 518 are connected to pressure while ports 520 are connected to exhaust. As a result of this rapid reciprocating or "dithering" of the valve members the opposite faces of the pistons 442 and 448 will be subjected to a series of very short pressure impulses, of equal duration and strength, the effects of which are balanced so that no appreciable movement of either piston is produced.

Considering now one of these valves, for example, the elevation valve which is operated by lever 610, if the left-hand end of this lever, which is connected to the bell crank 604 by link 608, is elevated slightly, by counterclockwise movement of the handle 420 as viewed in Fig. 18, the reciprocations of the valve member will be transferred to a locality nearer to the top of the valve housing. Now the duration and extent of the uncovering of the port 518 to exhaust will be decreased while the duration and extent of its uncovering to pressure will be increased. Likewise, the duration and extent of the uncovering of port 520 to exhaust will be increased while the duration and extent of its uncovering will be decreased. As a result of this, the pressure impulses which are imposed on the opposite sides of piston 442 will be unbalanced, those on the bottom face, as viewed in Fig. 18, now being stronger, due to the greater extent of the opening of port 518 to pressure than to exhaust and the correspondingly lesser extent of the opening of port 520 to pressure than to exhaust, and longer, due to the greater duration of the opening of this port to pressure than to exhaust, and the correspondingly lesser duration of the opening of port 520 to pressure than to exhaust. This unbalancing of the pressure impulses will cause piston 442 to move upwardly at a speed dependent upon the net difference between the impulses on its opposite faces. As will be apparent this difference will, in turn, depend upon the amount the left-hand end of the lever 610 was displaced, by movement of the control handle, from the position shown in Fig. 18. A similar result, in the opposite sense, will, of course, be produced by a downward displacement of the right-hand end of lever 610 by a clockwise movement of the control handle. Likewise, the operating lever 678 may be manipulated, by swinging the control handles to the right or left, to change the locality of the reciprocations of the valve member 522 of the azimuth rate valve.

These rate valves of the modified form of my invention hence operate like the rate valves of the first described embodiment to control the operation of the rate motors in accordance with the direction and extent of displacement of the control handles from neutral position. For satisfactory results the change in the speed of operation of the rate motors must be very accurately controlled and, under most conditions, the amount of change, at least for small movements of the control handles, is very small. As explained above, the desired accuracy and sensitivity of rate valve action is obtained in the valves employed in the first described embodiment by means of the exhaust control kerfs 336. This construction, however, requires very accurate machining and the narrow kerfs are quite likely to become fouled with sediment if used in systems in which proper filters are not provided.

The dither valve construction just described, and which is shown embodied in the modified form of the invention, not only avoids the aforementioned disadvantages but also provides improved operating characteristics, as will now be explained. As will be apparent from the manner in which the dither valve operates, a unit displacement of the left-hand end of a valve operating lever (Fig. 12) will produce a change in the rate of flow of pressure fluid which is equal to one-half of the change in rate of flow that would be obtained for the same displacement if the valve member were not being dithered. This is because of the fact that the dithering action keeps the valve closed for one-half of the time and open for the other half. Thus the effective valve opening is only one-half of the actual and the sensitivity of the valve is doubled. Likewise, with the square ended slits 518, 520 and straight sided piston portions 524, 526, which are relatively easy to machine accurately, and the dithering action of the valve member, a very accurate control over the rate of flow of pressure fluid through the valve is obtained since this rate is absolutely dependent upon the amount of displacement of the valve operating lever.

In valves in which the rate of flow depends in part on the shape of inlet or outlet ports, as for example the kerfs 336 in the valve piston portions of the valve member in the first described rate control valves, any inaccuracy in the machining of such ports will be reflected in the operation of the valve. Also, unless these ports, as well as the valve operating member, are very accurately machined, there is likely to be a "dead spot," i. e., small range of movement of the valve member with no resultant port opening, or a leakage through the valve, to one end or the other of the motor cylinders, when the valve member is in mid-position. Since the slightest displacement of the valve operating lever will, as has been already explained, result in an unbalancing of the pressure impulses, there is, practically at least, no such dead spot in the dither valve.

Furthermore, with the valve member continuously in motion there is no static friction, between the valve member and valve, to be overcome by the operator when he moves the control handles. Jerky motion of the control handles, which may be caused by static friction in the rate control valve is therefore avoided and a very smooth action obtained. Also, static friction in the rate motors, and in fact throughout the whole fluid-pressure system, is eliminated as a result of the action of the dither valves. The rapid application of pressure impulses alternately to the opposite sides of the rate motor pistons keeps these pistons always mobile and in a state of vibration, although the extent of movement is so slight as to be practically imperceptible. Accordingly, the static friction, between the pistons and their cylinders, is broken and these pistons are free to respond at once and to move in either direction when these impulses are unbalanced by the slightest movement of the control handle. Since the rate pistons are connected to the servo levers, which control the flow of pressure fluid to the elevation and azimuth motors, this effect is transmitted to the servo valves and, ultimately, to the pistons of the gun training motors.

Having thus described my invention, what is claimed as new and desired to be secured by Letters Patent of the United States is:

1. Control mechanism for power-operated gun-training apparatus having a gun to be trained, a

motor for training the gun and control means therefor including a member movable from a neutral position to determine the direction, speed and extent of movement of the gun by the motor, said mechanism comprising a manually shiftable member, movable at will by the operator, for selectively displacing the movable member from its neutral position to cause said motor to impart a corresponding training movement to the gun, and power-operated means under the control of said shiftable member for continuing the movement of said control member to cause the motor to continue the training movement of the gun at a rate dependent upon the extent of the initial movement of said shiftable member by the operator.

2. Control mechanism for power-operated gun-training apparatus having a gun mounted for training movements, a plurality of motors for moving the gun in different planes and separate control members, movable in opposite directions from neutral positions for determining the direction, speed and extent of training movement of the gun by each of said motors, said mechanism comprising a manually shiftable member movable by the operator in a plurality of planes corresponding to the different planes of training movement of the gun by said motors for selectively displacing said control members from their neutral positions to cause said motors to impart a corresponding training movement to said gun, and means operable in response to movement of said shiftable member for continuing movement of the control members to effect a continued training movement of the gun in the same direction and at a rate dependent upon the extent of the initial movement of said shiftable member by the operator.

3. Control mechanism for power-operated gun-training apparatus having a gun mounted for training movements, a fluid-pressure motor for moving the gun, a control valve and a valve-operating member movable from a neutral position to determine the direction, speed and extent of training movement of the gun by the motor, said mechanism comprising a manually shiftable member, movable at will by the operator, for selectively displacing said valve-operating member from its neutral position to cause said member to impart a corresponding training movement to the gun, and fluid-pressure-operated means under the control of said shiftable member for continuing the movement of the valve-operated member to cause said fluid-pressure motor to continue its training movement of the gun at a rate dependent upon the extent of the initial movement of the shiftable member by the operator.

4. Control mechanism for power-operated gun-training apparatus having a gun mounted for training movements, a plurality of fluid-pressure motors for training the gun in different planes, separate control valves for said motors, each including a valve-operating member movable from a neutral position to determine the direction, speed and extent of training movement of the gun by its respective motor, comprising, in combination, a manually shiftable member, movable at will by the operator, in a plurality of planes corresponding to the planes of training movement of the gun for selectively displacing said valve-operated members from their neutral positions to cause said motors to impart a corresponding training movement to the gun, and fluid-pressure-operated means operable in response to movement of said shiftable member for continuing the movement of the valve-operating mem-

bers to effect a continued training movement of the gun in the same direction and at a rate dependent upon the extent of the initial movement of said shiftable member by the operator.

5. Control mechanism for operating a plurality of members each movable in opposite directions from a neutral position to determine the direction, speed and extent of movement of one of a plurality of motors, comprising a plurality of differential means each having an output element associated with one of said movable members and two input elements, a single control handle connected to one of the input elements of each differential means, a plurality of auxiliary motors each connected to the other input element of one of said differential means, and means for controlling the direction and speed of movement of said auxiliary motors in accordance with the direction and extent of movement of the control handle.

6. Control mechanism for operating a plurality of members each of which is movable in opposite directions from a neutral position to determine the direction, speed and extent of movement of a device in a particular plane, comprising a plurality of differential means each having an output element associated with one of said movable members and two input elements, a single control handle connected to one of the input elements of each differential means, a plurality of auxiliary motors each connected to the other input element of one of said differential means, and means for controlling the direction and speed of movement of said auxiliary motors in accordance with the direction and extent of movement of the control handle by the operator.

7. Control mechanism for operating a plurality of members each movable in opposite directions from a neutral position to determine the direction, speed and extent of movement of one of a plurality of motors, comprising a plurality of differential means each having an output element associated with one of said movable members and two input elements, a single control handle connected to one of the input elements of each differential means, a plurality of fluid-pressure motors each connected to the other input element of one of said differential means, and valve means for controlling the direction and speed of movement of said fluid-pressure motors in accordance with the direction and extent of movement of the control handle by the operator.

8. Control mechanism for operating a mem-

ber movable in opposite directions from a neutral position, comprising a control handle, a fluid-pressure motor and differential means for transmitting movements of the handle and of the motor to said member, a valve having a valve member shiftable from a closed position for controlling the flow of pressure fluid to and exhaust from the opposite sides of the motor to control the direction and speed of its movements, a lever for operating said valve member, means for vibrating one end of said lever for rapidly reciprocating said valve member, equally on opposite sides of its closed position, to connect both sides of the motor alternately to pressure and exhaust, and means for positioning the other end of said lever, in accordance with movements of the control handle, thereby to change the position of said reciprocations and control the direction and speed of operation of said motor by varying the rate of flow of pressure fluid to and exhaust from opposite sides thereof.
